WILLIAM R. HEYLMUN, OF IOLA, KANSAS, ASSIGNOR OF ONE-HALF TO E. B. CARNEY,
OF WHEELING, WEST VIRGINIA.

MAGAZINE-PENCIL.

1,156,860.

Specification of Letters Patent.

Patented Oct. 12, 1915.

Application filed December 31, 1914. Serial No. 879,820.

To all whom it may concern:

Be it known that I, WILLIAM R. HEYLMUN, a citizen of the United States of America, and resident of Iola, county of Allen, and State of Kansas, have invented 5 certain new and useful Improvements in Magazine-Pencils, of which the following is a specification.

This invention relates to certain new and 10 useful improvements in magazine pencils, and the primary object thereof is to provide a pencil which has means for holding a plurality of points that are adapted to be used one at a time, the points being removed 15 from the container, and applied in position for use, as desired.

Referring to the drawings: Figure 1 is a side elevation of the invention; Fig. 2 is a longitudinal sectional view partly in side 20 elevation; Fig. 3 is a similar view completely in section; and Fig. 4 is a side elevation of a modified form of the invention.

Referring more particularly to the drawings, the reference numeral 1 designates the 25 casing of the pencil, interiorly threaded at its outer end 3 and provided with a cap 2 that serves to close the said end 3 of the casing 1. Adjacent the other end of the casing 1 is provided a partition 4 which 30 serves as one of the walls of a chamber or compartment 5 that contains the points 30 of lead. The casing 1 is provided adjacent the partition 4 with an annular bead 6, being reduced in diameter at 7, so that same 35 is of less diameter than the body portion of the casing 1. Rigidly secured to the reduced portion 7 of the casing 1 and projecting out therefrom is a pin 8, the purpose of which will be hereinafter described. A tubular 40 member or sleeve 10 is received within the reduced portion 7 of the casing 1, and is provided with an annular intermediate shoulder 11 which limits its inward movement within the casing 1 by engagement 45 with the end of the reduced portion 7. The tubular member 10 is tapered forwardly at 12, and is of truncated form having a free end 13. Slidable within the tapered portion 12 of the tubular member 10 is a tapered 50 block 15, which is pressed forwardly by means of a coil spring 16, one end 17 of the latter engaging the rear end of block 15 while the opposite end abuts the partition 4. Surrounding the reduced portion 7 of the 55 casing 1 is a sleeve 20 having the end 21

abutting bead 6 and provided with a bayonet slot 22 that receives the pin 8 for the purpose of holding the sleeve 20 in place on the casing 1. The forward portion of the sleeve 20 is tapered at 25 and extends beyond 60 the free end of the tapered portion 12 of the tubular member 10.

As shown in Figs. 2 and 3, the lead is in the form of conical or tapered bodies 30, the greatest diameter of which is in excess of 65 the diameter of the free or smallest end of the sleeve 20. In use, one of the lead points 30 is inserted in the reduced tapered portion 25 and is held in its forward position by means of the coil spring 16 which forces the 70 block 15 forwardly against the flat base end of the lead point 30. When it is desired to renew the point 30 for any cause, the sleeve 20 is turned and slid forwardly until the bayonet slot is disengaged from the pin 8, 75 whereupon the sleeve 20 is removed and the block 15 is caused to project from the tapered portion 12 of the sleeve 10 by the action of the spring. One of the points is then removed from the magazine 5 and 80 placed in the sleeve 20 following which the sleeve 20 is placed over the tapered portion 12 of the sleeve 10. The spring 16 is again placed under tension by reason of the lead engaging the block 15, thus always keeping 85 the lead in an advanced or forward position. After the sleeve 20 is placed in position over the reduced portion 7 of the casing 1, the bayonet slot 22 is again engaged with the pin 8, thus holding the parts in 90 their assembled position.

In the modified form shown in Fig. 4 in lieu of having one of the ends of the casing closed by the screw cap 2, the casing is provided with an elongated slot or opening 40, 95 over which is fitted a cap 41 provided with an elongated slot or opening 42 for registry with slot 40. In this modified form of the invention when it is desired to remove a piece of lead from the container or receptacle 5, the cap 41 is turned until its slot 42 is brought into register with the slot 40 in the casing 1, whereupon one of the points may be removed. By moving the slots 40 and 42 out of register, the opening into the casing 1 100 is closed, thus preventing accidental displacement of the lead points.

What is claimed is—

1. A magazine pencil comprising a tubular casing having a reduced extremity, a 110

partition in the casing, a tapering tubular member within the reduced portion of the casing, a tapered block conforming to said tubular member, a coiled spring having one 5 end bearing against said partition and its opposite end engaging said block to force the latter forward, a sleeve for carrying the lead points surrounding the reduced portion of the casing, said block engaging the lead 10 to force the latter forwardly, and means for securing the sleeve to the casing.

2. A magazine pencil comprising a casing, a tapering sleeve removably secured to one end of the casing, a writing point carried by 15 said sleeve, a second sleeve carried by the casing and lying within the first named sleeve, a block slidably mounted in the second sleeve and engaging the writing point, and means for maintaining said block in 20 engagement with the writing point.

3. A magazine pencil comprising a casing, a tapering sleeve carried thereby, a writing point mounted in the sleeve, a second sleeve carried by the casing and lying within the 25 first mentioned sleeve, a block carried by the second sleeve, and engaging the writing point to maintain same in operative position, and spring means for maintaining said block in engagement with the writing point.

4. A magazine pencil comprising a casing 30 having a reduced portion on one end thereof, a sleeve having a portion thereof formed to engage the reduced portion of the casing and having a tapering portion, a writing point carried by the tapering portion, a second 35 tapering sleeve within the first mentioned sleeve, a partition in the casing, a tapering block slidable in the second sleeve and engaging the writing point, and means engaging the partition and the tapering block to 40 secure the writing point in position.

5. A magazine pencil comprising a casing, a tapering sleeve carried by one end thereof, a writing point in the tapering sleeve, a second tapering sleeve lying within the first 45 named sleeve and carried by the casing, a tapering block carried by the second sleeve and engaging the writing point, a partition in the casing, and a coil spring having one end engaging the said sliding block and its 50 opposite end engaging said partition to hold the writing point in position.

In testimony whereof, I affix my signature in presence of two subscribing witnesses.

WILLIAM R. HEYLMUN.
